(57) **CLAIM**

The ornamental design for a modular video support frame member, as shown and described.

DESCRIPTION

FIG. 1 is a front perspective view of a modular video support frame member showing our new design; FIG. 2 is a front view thereof;

FIG. 3 is a top view thereof, the bottom view is a mirror image of the top view;

FIG. 4 is a right-side view thereof, the left-side view is a mirror image of the right-side view;

FIG. 5 is a rear view thereof;

FIG. 6 is an enlarged view of a portion of FIG. 2; and,

FIG. 7 is an enlarged view of a portion of FIG. 1.

The broken lines in the Figures are for the purpose of illustrating unclaimed portions of the modular video support frame member and form no part of the claimed design. The shade lines in the Figures show contour and not surface ornamentation. The modular video support frame member is shown with a symbolic break in its length. The appearance of any portion of the modular video support frame member between the break lines forms no part of the claimed design.
